EARL ELWOOD BASS, OF FORT MILL, SOUTH CAROLINA, ASSIGNOR TO DRAPER CORPORATION, OF HOPEDALE, MASSACHUSETTS, A CORPORATION OF MAINE

SHUTTLE-FEELER MECHANISM FOR LOOMS

Application filed January 29, 1930. Serial No. 424,265.

This invention relates to filling replenishing looms, and more particularly to the shuttle feeler mechanism.

It is now the ordinary practice to provide filling replenishing looms with a shuttle feeler which on call for replenishment of filling is moved from a frontward to a rearward position to ascertain if the shuttle has been properly boxed and if not to prevent operation of the replenishing mechanism. Such shuttle feelers are usually provided with a thread cutter for the purpose of cutting the outgoing thread between the selvage and the shuttle box, but this is not always necessary.

It may happen at times during the weaving operation and between calls for replenishment of filling that the shuttle will fail to fully enter the shuttle box or it may get trapped with a portion thereof extending from the shuttle box towards the cloth selvage, and in such case when the lay makes its forward beat-up movement the shuttle feeler is liable to be struck by the frontwardly moving shuttle, even though the shuttle feeler is in its normal frontward position, so that on further frontward movement of the lay, injury or breakage of parts may result.

One of the objects of the present invention, therefore, consists in a shuttle feeler mechanism wherein the shuttle feeler is mounted upon a shuttle feeler support which is itself mounted on the loom frame for movement towards and from the front of the loom, with the result that should the shuttle feeler encounter an improperly boxed shuttle, both the shuttle feeler and the shuttle feeler support may be moved frontwardly by the oncoming shuttle to thereby avoid breakage of or injury to parts.

More specifically stated, the shuttle feeler support which is mounted upon the loom frame for movement towards and from the front of the loom, is normally held in its rearward position for permissive frontward movement, while the shuttle feeler itself is normally held in front position with permissive yielding movement frontwardly.

The invention and novel features thereof will best be made clear from the following description and the accompanying drawings of one good practical form thereof.

In the drawings:

Fig. 1 is a sectional side elevation of portions of a filling replenishing loom provided with the present invention, the shuttle feeler being shown as in its rearward shuttle feeler position; and

Fig. 2 is a similar view showing the relation of parts when the shuttle feeler engages an improperly boxed shuttle as the lay moves frontwardly.

The loom frame 1 may be of usual construction and have mounted thereon the support 2 for the transfeerer 3. Extending downwardly from the hub portion 4 of the transfeerer is the arm 5 having pivoted to its lower end portion the dog 6 adapted to be engaged by a bunter 7 carried by the lay, provided the dog 6 has been moved into the path of the bunter on call for replenishment of filling.

The lay 8 is shown as carried by the usual lay swords 9 and is provided with the shuttle box 10, and the parts thus far described may be of usual construction which being now well understood in the art need no further explanation.

Mounted on the loom frame 1 is a shuttle feeler support 11 which is shown in the present instance of the invention as connected to the loom frame by a pivotal mounting 12, whereby the shuttle feeler support is capable of frontward swinging movement about its pivotal mounting responsive to a frontward pressure on the support.

The shuttle feeler support 11 has a rearwardly extending arm 13 provided with a lug 14 to which is connected one end of a spring 15, the other end of the spring being connected at 16 to a fixed point on the loom frame, the construction being such that the spring 15 normally holds the shuttle feeler support 11 in its rearward position with permissive movement frontwardly in opposition to the spring 15.

In order that the shuttle feeler support 11 may be maintained in its proper rearward

position during the weaving operation, a stop is provided for determining the rearward position of the shuttle feeler support. In the present instance of the invention, the stop consists of a block secured to the loom frame by a bolt 18 and the shuttle feeler support is provided with a cooperating stop constituted by a shoulder 19 which overlies the stop 17 when the shuttle feeler support is in its normal rearward position, as indicated in Fig. 1.

The shuttle feeler support 11 carries the shuttle feeler 20 which is pivotally mounted on the shuttle feeler support at 21, and the shuttle feeler extends upwardly, as usual, and has its rearwardly extending end portion 22 provided with the shuttle engaging jaws, which also constitute thread positioning means to position the thread for the action of the thread parter or thread parter and clamp.

The thread parter 23 has one of its parting members pivotally mounted on the shuttle feeler at 24 and extends frontwardly to form the toe 25 which may be engaged by the lay or a part carried thereby for operating the thread parter. The thread parter may be of any of the now well-understood constructions and needs no further explanation.

Secured to the shuttle feeler 20 at 26 is the slotted arm 27 which engages a pin 28 extending from the dog 6, the construction being such that should the shuttle feeler be moved rearwardly on call for replenishment of filling, the dog 6 will be moved into the position indicated in Fig. 1, to engage the bunter 7 carried by the lay, to thereby operate the transerrer.

Mounted on the loom frame is the transverse or rock shaft 29, as usual, and secured to the rock shaft is the arm 30, the rear end portion 31 of which overlies a pin 32 carried by the shuttle feeler. Cooperating with the end 31 of the arm 30 is a yielding member 33 which is shown as constituted by a rocking member mounted upon the arm 30 at 34 and having its frontwardly extending end 35 connected to a spring 36, the lower end of which is secured to a pin 37 on the loom frame, with the result that should the shuttle feeler be moved frontwardly by engagement with the shuttle, the member 33 will yield against the stress of the spring 36, as indicated in Fig. 2.

Preferably the spring 15 is stronger than the spring 36, so that should the shuttle feeler contact with an improperly boxed shuttle as the lay moves frontwardly, the shuttle feeler will first be moved frontwardly about its pivotal mounting 21 on the shuttle feeler support and then the shuttle feeler support 11 will come into action and permit the shuttle feeler to be moved further frontward by tilting or swinging movement of the shuttle feeler support, thereby providing sufficient frontward yielding movement of the shuttle

feeler by the combined action of the shuttle feeler support and shuttle feeler, to prevent damage or breakage of parts.

Extending upwardly from the shuttle feeler support is the guide member 38 which directs the shuttle feeler in its path of movement towards and from the front of the loom.

During normal weaving operations between calls for replenishment of filling, the shuttle feeler occupies its frontward or inoperative position, as usual, while the shuttle feeler support occupies its normal rearward position under the action of the spring 15, and should the shuttle feeler contact with an improperly boxed shuttle as the lay moves frontwardly, the shuttle feeler will yield at its pivotal mounting 21 on the shuttle feeler support against the stress of the spring 36, and as the lay moves frontwardly the shuttle feeler support will be turned about its pivotal mounting 12 against the stress of the spring 15, thereby permitting sufficient frontward movement of the shuttle feeler to prevent injury or breakage of parts.

On call for replenishment of filling, the rock shaft 29 will be turned or rocked, thereby moving the shuttle feeler to its rearward shuttle feeling position, and if at this time the shuttle feeler engages an improperly boxed shuttle as the lay moves frontwardly, the shuttle feeler will be first moved frontwardly against the stress of the spring 36, as indicated in Fig. 2, and the shuttle feeler support will also swing frontwardly about its pivotal mounting 12 to thereby permit the shuttle feeler sufficient frontward movement by the oncoming improperly boxed shuttle to prevent injury or breakage of parts, and since the dog 6 is connected to the shuttle feeler as above described, the shuttle feeler will swing the dog out of operation with the oncoming bunter 7 and filling replenishment will not be effected.

The invention herein described provides a simple and effective means for sufficient frontward movement of the shuttle feeler by an improperly boxed shuttle to avoid the injuries and breakage of parts that now frequently occur under these conditions, and while the present embodiment of the invention shows the shuttle feeler provided with a thread cutter, this may or may not be used within the true scope of the present invention.

What is claimed is:

1. In a shuttle feeler mechanism for looms, the combination of a feeler support mounted on the loom frame for movement towards and from the front of the loom, means acting yieldingly upon the support to normally maintain it in rearward position, a shuttle feeler pivotally mounted on the support for movement relative thereto towards and from the front of the loom, and yielding means connected to the feeler permitting frontward

movement thereof relative to and with said movable support should the feeler encounter the shuttle as the lay moves frontwardly.

5 2. In a shuttle feeler mechanism for looms, the combination of a feeler support mounted on the loom frame for movement towards and from the front of the loom, a spring normally acting to hold the feeler support in rearward position and a shuttle feeler mounted 10 on the support for movement relative thereto towards and from the front of the loom that both the shuttle feeler and feeler support may move frontwardly to obviate breakage or injury to parts should the shuttle feeler 15 contact with the shuttle as the lay moves frontwardly.

3. In a shuttle feeler mechanism for looms, the combination of a feeler support mounted 20 on the loom frame for movement towards and from the front of the loom, means acting yieldingly upon the support to normally maintain it in rearward position, a stop for defining the rearward position of the feeler support under the stress of the yieldingly 25 acting means, a shuttle feeler pivotally mounted on the support for movement relative thereto towards and from the front of the loom, and yielding means connected to the feeler permitting frontward movement 30 thereof relative to and with said movable support should the feeler encounter the shuttle as the lay moves frontwardly.

4. In a shuttle feeler mechanism for looms, the combination of a feeler support mounted 35 on the loom frame for movement towards and from the front of the loom, a spring normally acting to hold the feeler support in rearward position, a stop for limiting the rearward movement of the feeler support, and a 40 shuttle feeler mounted on the support for movement relative thereto towards and from the front of the loom that both the shuttle feeler and feeler support may move frontwardly to obviate breakage or injury to parts 45 should the shuttle feeler contact with the shuttle as the lay moves frontwardly.

5. In a shuttle feeler mechanism for looms, the combination of a feeler supporting bracket pivotally mounted on the loom frame 50 for movement towards and from the front of the loom, a shuttle feeler pivotally mounted on the pivoted bracket, means normally acting to hold the shuttle feeler in front position including a yielding member permitting further frontward movement of the feeler, and a spring normally acting to hold the feeler supporting bracket in its rearward position with permissive frontward movement that both the shuttle feeler and shuttle supporting 55 bracket may be displaced frontwardly to prevent injury to parts when the shuttle feeler contacts with the shuttle as the lay moves frontwardly.

6. In a shuttle feeler mechanism for looms, 60 the combination of a feeler supporting

bracket pivotally mounted on the loom frame for movement towards and from the front of the loom, a shuttle feeler pivotally mounted on the pivoted bracket, means normally acting to hold the shuttle feeler in front position including a yielding member permitting further frontward movement of the feeler, a spring normally acting to hold the feeler supporting bracket in its rearward position with permissive frontward movement 70 that both the shuttle feeler and feeler supporting bracket may be displaced frontwardly to prevent injury to parts when the shuttle feeler contacts with the shuttle as the lay moves frontwardly, and a bracket stop to 75 limit the normal position of the feeler supporting bracket.

7. In a shuttle feeler mechanism for looms, the combination of a feeler supporting bracket pivotally mounted on the loom frame 80 for swinging movement towards and from the front of the loom, a shuttle feeler pivotally mounted on the feeler supporting bracket at a point above the pivotal mounting of the bracket, means including a yielding member 85 normally acting to hold the shuttle feeler in front position, and yielding means normally acting to hold the bracket in its rearward position with permissive frontward movement that the shuttle feeler and the 90 feeler supporting bracket may yield frontwardly should the shuttle feeler engage the shuttle as the lay beats up.

In testimony whereof, I have signed my name to this specification.

EARL ELWOOD BASS.
